UNITED STATES PATENT OFFICE

NORMAN H. SAUNDERS, OF HOMEWOOD, ILLINOIS, ASSIGNOR TO RESERVE HOLDING COMPANY, OF KANSAS CITY, MISSOURI, A CORPORATION OF DELAWARE

TELEPHONE TRUNKING SYSTEM

Application filed April 28, 1928. Serial No. 273,512.

This invention relates to telephone systems in general, but is concerned more particularly with trunking systems in telephone exchange systems comprising both manual and automatic exchanges.

In telephone exchange practice, it is a recognized fact that when inter-office trunk lines are in close proximity to high tension power lines, line noises due to inductive interferences are greatly reduced if all ground and battery connections are disconnected from the interoffice trunk conductors during the period of conversation. In the application of Clarence E. Lomax, Serial No. 184,197, filed April 16, 1927, a trunking arrangement for two-way trunks between two automatic exchanges is shown in which the normal battery and ground connections are disconnected from the trunk during the period of conversation.

This invention may be considered an improvement and further development of the arrangement shown in the above reference, its object being the provision of a trunking system in which the normal ground and battery connections are disconnected from the inter-office trunk line during the period of conversation when the call is extended from a manual to an automatic exchange or from an automatic to a manual exchange, and further, the provision of a trunking system in which when a call is extended from one exchange to another exchange by way of an intermediate exchange, the normal ground and battery connections are disconnected from the trunk between the first exchange and the intermediate exchange as well as from the trunk between the intermediate exchange and the second exchange during the period of conversation. In telephone parlance a trunk free from all battery and ground connections is known as a dry trunk, and the operation of disconnecting the normal battery and ground connections from the trunk is known as cutting the trunk dry.

This invention and its various features will be described in detail in the following specification with the aid of the accompanying drawings comprising Figs. 1 and 2. These drawings, when Fig. 1 is placed to the left

of Fig. 2 show by means of the usual schematic circuit diagrams a preferred embodiment of the invention.

The system chosen to illustrate this invention comprises three exchanges, two manual exchanges and an automatic exchange with interoffice trunks between the automatic exchange and each manual exchange, although the invention is in no way limited to any particular size system. The apparatus shown to the left of the dotted vertical line in Fig. 1 is located in the first manual exchange, which will be referred to as exchange A. The apparatus shown to the right of the dotted vertical line in Fig. 1 and to the left of the dotted vertical line in Fig. 2 is located in the automatic exchange, which will be referred to as exchange B; and the apparatus indicated to the right of the dotted vertical line in Fig. 2 is located in the second manual exchange, which will be referred to as exchange C. The trunk comprising conductors 81 and 82 is one of the trunks extending from the exchange A to exchange B. This trunk is accessible at exchange A at jack J', and terminates at exchange B in the selector S by way of the outgoing repeater OR' and the incoming repeater IR. The trunk comprising conductors 281 and 282 is one of the trunks extending from exchange C to exchange B. This trunk is accessible at exchange C at jack J², and terminates at exchange B in the selector S' by way of the outgoing repeater OR and the incoming repeater IR'. A trunk relay group, such as relay group TRG is associated with the manual end of each inter-office trunk. The trunk relay group TRG', the incoming repeater IR', and the outgoing repeater OR', indicated only by rectangles, are similar to the trunk relay group TRG, the incoming repeater IR, and the outgoing repeater OR, respectively.

The local automatic switch train in exchange B is diagrammatically shown at the bottom of Fig. 2, comprising the individual line switch LS, the local selector S², and the connector C. The selectors, such as selector S, have access in their banks to the trunks to exchange C by way of the outgoing repeaters, such as repeater OR, and also have

access to the connectors in exchange B. The selectors, such as selectors S', have access to the trunks to exchange A by way of the outgoing repeaters, such as repeater OR', and also have access to the connectors of exchange B. The local selectors, such as selector S², in addition to having access to the connectors in exchange B, also have access to the trunks to exchange A and to the trunks to exchange B by way of the outgoing repeaters.

In the description it is assumed that the selectors and connectors in exchange B are of the Strowger vertical and rotary type, and that the cords used by the operators in the manual exchanges are of the type which have battery and ground normally connected to the tip and ring conductors, respectively, and which impulse over the tip conductor and maintain ground connected to the ring conductor during the impulsive period. The cord circuit O, shown in Fig. 1 is a skeleton of a cord of this type. Another similar cord circuit is indicated in Fig. 2 at O'.

A further understanding of the invention is obtainable most easily by following through the operations performed in the establishment of various connections. For this purpose it will be assumed that the operator at exchange A has received a call for a subscriber at exchange C. It will be assumed that she has answered the incoming call by means of the cord circuit O. To further extend the connection, the operator inserts the calling plug P' of the cord circuit O into the jack of an idle trunk extending to exchange B, the jack J' for example. Inserting plug P' into jack J' closes a circuit for relay 5 in series with sleeve relay 60 over the sleeve conductor of plug P' and jack J'. Relay 5 operates and closes a circuit for relay 20 and lamp L at contacts 6. Relay 20 operates and bridges the calling device across the tip and ring conductors of plug P' at contacts 21 and 23. Relay 60, in operating over the above circuit, closes points in the talking circuit at contacts 62 and 65 and closes a circuit for relay 40 at contacts 64 which includes contacts 43, ring of jack J' and plug P', contacts 23, and off-normal contacts 16 of the calling device D. Relay 40 operates and closes a holding circuit for itself at contacts 42, disconnecting itself from the ring conductor by separating contact 43, and closes the circuits for relays 55 and 75 at contacts 41. Relay 55 operates and by separating contacts 76 and 79 disconnects relay 70 from the trunk conductors and by closing contacts 77 and 78 further prepares the talking circuit. Relay 55 operates and by closing contacts 56 closes the bridge across the trunk conductors 81 and 82, thereby closing a circuit for relay 50 in series with the line relay 130 of the incoming repeater IR at exchange B.

Relay 130 operates and closes the circuit of relay 135 at contacts 132, and closes the

bridge across conductors 141 and 142 at contacts 131. As a result, the line and the release relays in the selector S operate to prepare the selector S for operation. Relay 135 of the repeater IR, in operating, prepares the circuit of relay 105 at contacts 136, and grounds the release conductor 202' at contacts 137 at the same time also completing the circuit for the polarizing winding of relay 100. The presence of ground potential on conductor 202' marks this trunk busy.

After inserting plug P' into jack J', the operator at exchange A dials the number assigned to exchange C. When the calling device D is moved off-normal, contacts 16 are opened and contacts 18 are closed, thereby placing ground potential on the ring conductor. This causes the operation of relay 30, battery potential being connected to the upper terminal of its winding by way of contacts 36 and 42. Relay 30, in operating, connects the impulsive relay 55 to the tip conductor at contacts 31, relay 55 thereafter being energized from ground at the impulsive springs of the calling device D. When the calling device is released, the circuit of relay 55 is opened a number of times corresponding to the digits for which the calling device was positioned. Relay 55 deenergizes and reenergizes a corresponding number of times, opening the circuit of line relay 130 at the exchange B at contacts 56 at each deenergization. Line relay 130 repeats the impulses to selector S at contacts 131. The selector S then operates in the usual manner, raising its wipers opposite the level corresponding to the digit dialed and then selecting an idle trunk in that level. During the impulsive period, slow-to-release relay 105 is maintained operated, its circuit being closed each time that relay 130 deenergizes. Relay 105, in operating, short-circuits the left hand windings of repeating coil R' at contacts 106 and 107, and short-circuits the entire right hand side of this repeating coil at contacts 108, the purpose being to improve the impulsive circuit.

It will be assumed that the trunk selected is the one comprising conductors 201, 202, and 203, which extends to exchange C by way of the outgoing repeater OR. When this trunk is seized, line relay 220 of the repeater OR closes the circuit of relay 230. Relay 230 operates and places ground on the release conductor 202 at contacts 231 to hold the selector S operated. At contacts 232 the circuit of the cut-off relay 240 is closed. Relay 240, in operating disconnects the repeater IR' from the trunk conductors 281 and 282 and completes the signalling circuit by closing contacts 242 and 243. Ringing current from the generator G is now supplied to the trunk conductors and causes the operation of the relay in the trunk relay group TRG' corresponding to relay 70 of the trunk relay group TRG. This relay operates and closes

a locking circuit for itself at contacts corresponding to contacts 72, and closes a circuit for lamp L^2 at contacts corresponding to contacts 71.

5 After dialling the digit, the operator at exchange A presses key K' . This operation closes the circuit of the lower winding of relay 10. Relay 10 then operates and disconnects relay 5 from the sleeve of plug P' and 10 closes a holding circuit for itself to the sleeve of P' by closing contact 11, opens the circuit of relay 20 by separating contact 14 and closes a new circuit for lamp L at contacts 13. Relay 20 then deenergizes and 15 disconnects the calling device D from the tip and ring conductors of plug P' and closes points in the talking connection by closing contacts 22 and 24. Relay 2 is bridged across the conductors of the cord, but since relay 50 is operated, holding the bridge across the tip and ring of jack J' open at contacts 51, relay 20 remains deenergized and the lamp L 20 remains lighted.

Upon noting the lighted condition of 25 lamp L^2 , the operator at exchange C answers the call by inserting the answering plug of an idle cord such as the plug P^3 (which corresponds to plug P of cord circuit O) into jack J^2 . The sleeve relay corresponding to 30 relay 60 then energizes over the sleeve conductor and causes the operation of the relay corresponding to relay 40 by closing contacts corresponding to contacts 64, and closes points in the talking circuit by closing contacts corresponding to contacts 62 and 65. The relay corresponding to relay 40, in operating, closes the circuit of the relays corresponding to relays 75 and 55, at contacts corresponding to contacts 41. These relays upon operating 35 complete the talking circuit, closing a bridge across the trunk conductors 281 and 282. The closing of the bridge across the trunk conductors closes a direct current circuit for the lower winding of ring-cut-off relay 210 at exchange B. Relay 210 thereupon operates, closing a locking circuit for itself at contacts 213, opening the ringing circuit and disconnecting battery and ground from the 40 trunk conductors by separating contacts 211 and 219, and closing points in the talking circuit at contacts 212 and 218. Furthermore, by separating contacts 215 and 217 and closing contacts 214 and 216, relay 210 reverses the current over the conductors 141 and 142 and through the upper winding of 45 polarized relay 100. Relay 100, not having responded previously, now operates and by separating contacts 102 opens the circuit of relay 135 and by closing contacts 101 closes the circuit of relay 120. Relay 120 operates, disconnecting the line relay 130 from the 50 trunk conductors extending to exchange A by separating contacts 122 and 125 and bridging relay 110 across the trunk conductors by closing contacts 123 and 124. At contacts

121 the contacts 131 are shunted and at contacts 126 ground potential is maintained on the release conductor 202' to maintain the talking circuit closed and the trunk marked busy after relays 130 and 135 restore. Relay 70, 110, of course, does not energize at this time since no battery is connected to the trunk conductors.

As soon as relay 130 is disconnected from the trunk conductors 81 and 82, relay 50 at exchange A falls back and closes a direct current bridge across the tip and ring of jack J' , at contact 51, thereby closing and energizing circuit for relay 2 of the cord circuit O. Relay 2, in operating, opens the circuit of lamp L at contacts 3, thereby extinguishing the lamp. The extinguishment of lamp L at this time signals the operator at exchange A that the call has been answered. To converse with the operator at exchange B the 85 operator at exchange A merely operates her listening key K to connect her telephone set to the talking connection.

It should be particularly noted that both the trunk from exchange A to exchange B 90 and also the trunk from exchange B to exchange C have been cut dry, this having taken place responsive to the call being answered at exchange B. That is, when the operator at exchange B answered the call the ring-cut-off relay 210 at exchange B disconnected the exchange battery normally bridged across the conductors 281 and 282 from the trunk conductors and reversed the current over the conductors 141 and 142 which caused the operation of the polarized relay 100 in the repeater IR, which in turn caused the disconnection of the exchange battery and line relay 130 from the trunk conductors 81 and 82 extending to exchange A. 105

The operator at exchange C then completes the connection to the desired subscriber in the usual manner.

At the termination of the conversation between the two subscribers, and after the operators have received the usual disconnect signals, both operators will remove the plugs of their cords from the jacks of the trunks used in the connection. When the plug P' is removed from jack J' , the circuit of relay 60 is opened. Relay 60 deenergizes and opens the circuit of relay 40. Relay 40 is slow to release and therefore maintains the circuit of relay 75 closed an interval after its own circuit is opened. During the time that relay 75 is maintained operated after relay 60 has restored, battery and ground are connected to trunk conductors 81 and 82 by way of contacts 61 and 66. This causes the operation of relay 110 bridged across the trunk conductors during the period of conversation at the exchange B. Relay 110, in energizing, 110 opens the circuit of relay 120 at contacts 113 and bridges itself across the conductors 81 and 82 independent of the contacts of relay 125 130

120 at contacts 111 and 114, and also connects ground to release conductor 202' at contacts 116. Relay 120, in restoring, opens the bridge across conductors 141 and 142 thereby opening the circuit of relay 220 of the outgoing repeater OR. Relay 220 deenergizes and opens the circuit of relay 230. Relay 230, in deenergizing, removes ground from the release conductor 202 at contacts 231, thereby causing the release of the selector S, and also opens the holding circuit of relays 210 and 240 by separating contacts 232.

As soon as relay 75 at exchange A restores, ground and battery are again disconnected from the trunk conductors 81 and 82, and the circuit of relay 110 of repeater IR at exchange B is opened. Relay 110, in deenergizing, again connects the line relay 130 across the trunk conductors 81 and 82 and removes ground potential from the release conductor 202' at the same time opening the circuit of the polarizing winding of relay 100 at contacts 116. Both trunks are thus placed in their normal condition. The purpose of causing relay 110 when operated to bridge itself across the trunk conductors 81 and 82 is primarily to maintain ground on the release conductor 202' to keep this trunk marked busy until after relay 75 at exchange A has restored.

Connections may be established from exchange C to exchange A over these same two trunk lines, and the operations performed will be the same as those described above. Such a connection, however, would extend by way of the incoming repeater IR', selector S', and the outgoing repeater OR'.

In this system, the subscribers in the automatic exchange B may also extend connections to either the manual exchange A or the manual exchange B, since the banks of the selectors such as selector S and the selectors such as selector S' are multiplied with the banks of the local selectors. To extend a connection to the exchange C, for example, a subscriber at exchange B merely removes his receiver and dials the digit assigned to the exchange to which he wishes to extend a connection. A selector such as selector S² operates and raises its wipers to the level corresponding to the digit dialled and then selects a trunk to the exchange C. The outgoing repeater of the trunk selected operates in the same manner as when selected by a selector such as the selector S. The reversal of current when the ring cut-off relay operates responsive to the answering of the call has no effect other than to cause the calling subscriber's meter to operate if he is a measured service subscriber.

Connections may also be completed from either manual exchange to a subscriber at the automatic exchange. To extend a connection to a subscriber at exchange B, the operator at exchange A follows the same pro-

cedure as she did in extending a connection to exchange C, except that she dials the complete number of the called subscriber. If the trunk comprising conductors 81 and 82 is used, selector S operates responsive to the first digit of the number to extend the connection to an idle connector of the proper group; and the connector operates responsive to the last two digits to extend the connection to the called subscriber's line and signal the called subscriber. When the called subscriber answers, the connector reverses the current over the trunk to the selector, which causes polarized relay 100 in the repeater IR to operate with the results previously described.

This completes the description of this invention. What is considered new and is desired to have protected by Letters Patent is specifically stated in the appended claims.

What is claimed is:

1. In a telephone system, a trunk line extending from a first to a second exchange, a second trunk line extending from the second exchange to a third exchange, an automatic switch at the second exchange terminating said first trunk line, means for operating said switch to connect with said second trunk line to extend a call from the first exchange to the third exchange, a battery at said second exchange connected to both said trunk lines, and means responsive to the answering of the call for disconnecting said battery from both of said trunk lines.

2. In a telephone system, a trunk line extending from a first to a second exchange, a second trunk line extending from the second exchange to a third exchange, an automatic switch at the second exchange terminating said first trunk line, means for operating said switch to connect with said second trunk line to extend a call from the first exchange to the third exchange, a battery at said second exchange connected to both said trunk lines, means responsive to the answering of the call for disconnecting said battery from both of said trunk lines, a signal control relay at the first exchange, and means responsive to the disconnection of said battery from the first trunk for actuating said signal control relay.

3. In a telephone system, a trunk line extending from a first to a second exchange, a second trunk line extending from the second exchange to a third exchange, an automatic switch at the second exchange terminating said first trunk line, means for operating said switch to connect with said second trunk line to extend a call from the first to the third exchange, a battery at the second exchange, a line relay normally connected to the first trunk line in series with said battery for controlling the operation of said switch, means for signalling over said second trunk line, a cut-off relay and means for connecting it to the second trunk line in series with said bat-

- tery when a call is extended from said second trunk line, said cut-off relay being responsive to the answering of the call for interrupting the signalling and for disconnecting said battery from said second trunk line, and means responsive to the operation of said cut-off relay for disconnecting said battery from said first trunk line.
4. In a telephone system, a trunk line extending from a first exchange to a second exchange, a repeater at the second exchange terminating said trunk line, an automatic switch, a pair of conductors extending from said repeater to said switch, a second trunk line extending from the second exchange to a third exchange, means for operating said switch to connect with said second trunk line to extend a call from the first to the third exchange, a battery at the second exchange, means for establishing a flow of current over said conductors, a line relay normally connected to the first trunk line in series with said battery for controlling the operation of said switch, means for signalling over said second trunk line, a cut-off relay and means for connecting it to the second trunk line in series with said battery when a call is extended over the second trunk line, said cut-off relay being responsive to the answering of the call for interrupting the signalling, for disconnecting said battery from said second trunk line, and for reversing the flow of current in said conductors, and means responsive to said reversal of current for disconnecting said battery and said line relay from said first trunk line.
5. In a telephone system, two serially related trunk lines for extending a call, a battery normally bridged across the conductors of each of the trunk lines, and means responsive to the answering of the call for disconnecting said battery from the conductors of both trunk lines.
6. In a telephone system, means including two serially related trunk lines for extending a call, the first trunk line comprising two inductively connected sections, means responsive to the initiation of the call for producing a flow of current in the two sections of the first trunk line, and responsive to the answering of the call for producing a flow of current in the second trunk line, means responsive to the flow of current in the second trunk line for reversing the current in the second section of the first trunk line, and means responsive to the reversal of current in the second section of the first trunk line for interrupting the flow of the current in the first section of the first trunk line.
7. In a telephone system, a trunk line terminating in an automatic switch, a second trunk line, a battery connected to both trunk lines, means controlled by successively interrupting a flow of current from said battery over said first trunk line for operating
- said switch to connect with said second trunk line to extend a call, means responsive to the answering of the call for disconnecting said battery from both said trunk lines, and means for maintaining said switch operated independent of the existence of a flow of current over either trunk line.
8. In a telephone system, a trunk line extending from a first to a second exchange, a second trunk line extending from the second exchange to a third exchange, an automatic switch at the second exchange terminating said first trunk line, means for operating said switch to connect with said second trunk line to extend a call from the first to the third exchange, a battery at the second exchange, a line relay normally connected to the first trunk line in series with said battery for controlling the operation of said switch, means for signalling over said second trunk line, a cut-off relay and means for connecting it to the second trunk line in series with said battery when a call is extended over said second trunk line, said cut-off relay being responsive to the answering of the call for interrupting the signalling and for disconnecting said battery from said second trunk line, means responsive to the operation of said cut-off relay for disconnecting said battery from said first trunk line, a second battery at the first exchange and means for momentarily connecting it to said first trunk line, and means at the second exchange responsive to the momentary connection of said second battery to said first trunk line for causing the release of said switch.
9. In a telephone system, a trunk line terminating in an automatic switch, a second trunk line, a battery connected to both trunk lines, means controlled by successively interrupting a flow of current from said first trunk line for operating said switch to connect with said second trunk line to extend a call, means responsive to the answering of the call for disconnecting said battery from both said trunk lines, means for maintaining said switch operated independent of the existence of a flow of current over either trunk line, a second battery, means for momentarily connecting it to said trunk line at the termination of the call, and means responsive to the connection of said second battery to said trunk line for releasing said switch.
10. In a telephone system, two serially related trunk lines for extending a call, a battery normally bridged across the conductors of each of the trunk lines, means responsive to the answering of the call for disconnecting said battery from the conductors of both trunk lines, a second battery, means for momentarily connecting said second battery to the first trunk line, and means responsive to the momentary connection of said second battery to the first trunk line for disabling said

first means to cause said first battery to be again bridged across both trunk lines.

11. In a telephone system, means including two serially related trunk lines for extending a call, the first trunk line comprising two inductively connected sections, means responsive to the initiation of the call for producing a flow of current in the two sections of the first trunk line, and responsive to the answering of the call for producing a flow of current in the second trunk line, means responsive to the flow of current in the second trunk line for reversing the current in the second section of the first trunk line, means responsive to the reversal of current in the second section of the first trunk line for interrupting the flow of current in the first section of the first trunk line, means responsive to the termination of the call for again producing a flow of current in the first section of the first trunk line, and means responsive to the second flow of current in the first section of the first trunk line for interrupting the flow of current in the second section of the first trunk line.

12. In a telephone system, two serially related trunk lines for extending a call, a battery normally bridged across the conductors of both trunk lines, means responsive to the answering of the call for disconnecting said battery from the conductors of each trunk line, a second battery, means for momentarily connecting said second battery to the first trunk line, a relay responsive to the connection of said second battery to the first trunk line, means responsive to the energization of said relay for causing said first battery to be again bridged across the second trunk line, and means responsive to the deenergization of said relay for causing the first battery to be again bridged across the first trunk line.

13. In a telephone system, a trunk line terminating in an automatic switch, a line relay and a battery bridged across the conductors of said trunk line in series, means including said line relay for operating said switch to extend a call, means responsive to the answering of the call for disconnecting said line relay from the conductors of said trunk line, a second relay and means for momentarily energizing it at the termination of the call, means responsive to the energization of said relay for releasing said switch, and means responsive to the deenergization of said relay for causing said line relay and said battery to be again bridged across the conductors of said trunk line.

14. In a telephone system, a trunk line and means for seizing it to extend a connection, a battery connected to said trunk line to furnish current for controlling the establishment of the connection, means for marking said trunk busy when it is seized, means responsive to the answering of the call for disconnecting said battery from said trunk line,

means for producing a momentary flow of current over said trunk line, a relay responsive to said momentary flow of current for effecting the reconnection of said battery to said trunk line, and contacts on said relay for maintaining said trunk line marked busy until the termination of said momentary flow of current.

15. In a telephone system, a trunk line, a cord circuit and means for connecting it to said trunk line, a self-locking relay, a sleeve relay responsive to the connection of said cord circuit to said trunk for closing an initial energizing circuit including one talking conductor of said trunk line for said self-locking relay, a third relay, a calling device in the cord circuit, means responsive to the movement of said calling device off normal for closing a circuit including said talking conductor and contacts on said self-locking relay for said third relay, an impulsing relay, and means controlled by said third relay for connecting said impulsing relay to the other talking conductor of said trunk line to place it under the control of said calling device.

16. In a telephone system, a trunk line, a cord circuit and means for connecting it to said trunk line, a self-locking relay, a sleeve relay responsive to the connection of said cord circuit to said trunk for closing an initial energizing circuit including one talking conductor of said trunk line for said self-locking relay, a third relay, a calling device in the cord circuit, means responsive to the movement of said calling device off normal for closing a circuit including said talking conductor and contacts on said self-locking relay for said third relay, an impulsing relay, means controlled by said third relay for connecting said impulsing relay to the other talking conductor of said trunk line to place it under the control of said calling device, a battery, and means controlled jointly by said sleeve relay and said self-locking relay for momentarily connecting said battery to said trunk line.

17. In a telephone system, a trunk line connecting a first and a second exchange, a second trunk line connecting the second exchange to a third exchange, means including said trunk lines for extending a call from the first exchange to the third exchange, a battery connected to said trunk lines, and means responsive to the answering of the call for disconnecting said battery from both of said trunk lines.

18. In a telephone system, a trunk line connecting a first and a second exchange, a second trunk line connecting the second exchange to a third exchange, means including said trunk lines for extending a call from the first to the third exchange, a battery connected to said trunk lines, means responsive to the answering of the call for disconnecting

said battery from both of said trunk lines, and means responsive to the termination of the call for again connecting said battery to said trunk lines.

5 19. In a telephone system, a trunk line connecting a first and a second exchange, a second trunk line connecting the second exchange to a third exchange, means including said trunk lines for extending a call from 70
10 said first to said third exchange, a battery connected to said trunk lines, means for signalling said third exchange, a cut-off relay in said second exchange responsive to the answering of the call, and means controlled by 75
15 said cut-off relay for disabling said signalling means and for disconnecting said battery from said trunk lines.

20. In a telephone system, a trunk line comprising two inductively connected sections 20 used to extend a call, a battery normally bridged across each of said sections, means responsive to the answering of the call for reversing the battery in the second section of said trunk line, and means responsive to 25
25 the reversal of battery in the second section of said trunk line for disconnecting said battery from the first section of said trunk line.

21. In a telephone system, a trunk line comprising two inductively connected sections 30 used to extend a call, a battery normally bridged across each of said sections, means responsive to the answering of the call for reversing the battery in the second section of said trunk line, means responsive to the reversal of battery in the second section of said trunk line for disconnecting said battery from the first section of said trunk line, and means responsive to the termination of the call for again connecting said battery to the two sections of said trunk line.

40 22. In a telephone system, a trunk line comprising two inductively connected sections used to extend a call, a battery normally connected to each of said sections, means responsive to the answering of the call for reversing the battery in the second section of said trunk line, a relay responsive to said reversal of battery, a second relay, and means responsive to the energization of said first relay for disconnecting said battery from the first section of said trunk line and for bridging said second relay across the conductors thereof.

45 23. In a telephone system, a trunk line comprising two inductively connected sections used to extend a call, a battery normally connected to each of said sections, means responsive to the answering of the call for reversing the battery in the second section of 50
55 said trunk line, a relay responsive to said reversal of battery, a second relay, means responsive to the energization of said first relay for disconnecting said battery from the first section of said trunk line and for bridging said second relay across the conductors 60
65 thereof.

thereof, means for momentarily energizing said second relay at the termination of the call, and means responsive to the operation of said second relay for again connecting said battery to the first section of said trunk line.

70 24. In a telephone system, a trunk line comprising two inductively connected sections and terminating in an automatic switch, means including said trunk line and said switch for extending a call, a battery normally connected to each of the sections of said trunk line, means responsive to the answering of the call for reversing the battery in the second section of said trunk line, a relay responsive to said reversal of battery, a second relay, means responsive to the energization of said first relay for disconnecting said battery from the first section of said trunk line and for bridging said second relay across the conductors thereof, a second battery, means responsive to the termination of the call for momentarily connecting said second battery to the first section of said trunk line to operate said second relay, means responsive to the energization of said second relay for releasing said switch, and means responsive to the deenergization of said second relay for again connecting said first battery to the two sections of said trunk line.

80 90 95 100 105 110 115 120 125 130
25. In a telephone system, a trunk line, a cord circuit and means for connecting it to said trunk line, a calling device in said cord circuit, an impulsing relay, means responsive to the connection of said cord to said trunk line and the movement of said calling device off normal for completing a dialling circuit including said calling device, one talking conductor of said trunk line and said impulsing relay, a battery, and means responsive to the disconnection of said cord from said trunk line for momentarily bridging said battery across the conductors of said trunk line.

In witness whereof, I hereunto subscribe my name this 25th day of April, A. D. 1928.

NORMAN H. SAUNDERS.
